UNITED STATES PATENT OFFICE.

JAMES J. MAHONY, OF AKRON, OHIO.

CATCH-BASIN.

SPECIFICATION forming part of Letters Patent No. 634,011, dated October 3, 1899.

Application filed February 6, 1899. Serial No. 704,705. (No model.)

To all whom it may concern:

Be it known that I, JAMES J. MAHONY, a citizen of the United States, residing at Akron, in the county of Summit and State of Ohio, have invented a certain new and useful Improvement in Catch-Basins, of which the following is a specification.

My invention has relation to improvements in catch-basins for receiving surface water, particularly on streets from which it passes to a sewer; and the objects of my invention are to produce an improved basin that will take the surface water mingled with dirt and rubbish and from which it can entirely escape through a screen that will retain all rubbish that might tend to clog the sewer to be removed by other means, to provide adjustable means for trapping the pipe leading to the sewer, to so construct and arrange the various parts that the overflow of the basin in excessive rainfalls will wash the screen, and to provide means for washing the screen at other times, the general object being to secure a sanitary catch-basin.

To the aforesaid purpose my invention consists in the peculiar and novel construction, arrangement, and combination of the various parts hereinafter described and then specifically pointed out in the claims, reference being had to the accompanying drawings, forming a part of this specification.

In the accompanying drawings, in which similar reference-numerals indicate like parts in the different views, Figure 1 is a portion of the interior of a catch-basin provided with my improvement, and Fig. 2 a view of the door to close the opening for adjusting the trap.

Referring to the figures, 1 is the wall of the catch-basin, built into and forming a part of which is a hollow box or shaft 2. This shaft is preferably square, although experience may determine a different shape will be better for the purpose. On the outside of this shaft are flanges 3 to retain it in the wall. The lower part 4 of this shaft is bent outward and upward and terminates in a cylindrical end, by which it is united with the branch pipe 5, leading to the sewer.

Attached to the lower part of the back wall of the shaft is a plate 6, having in its upper end slots to receive binding-bolts 7, by

which it is made vertically adjustable. The edges of this plate 6 fit the sides of the shaft, and by this means the plate and curved part 55 constitute a trap to prevent the entrance of gas from the sewer to the catch-basin. The front wall of this shaft is perforated with a series of openings 8, narrower toward the interior of the basin, so that water passing 60 through them from the basin will not become clogged with rubbish. In the lower end of the front wall is an opening 9, by which the bolts 7 and plate 6 may be reached for adjustment, and this opening is closed by a door 10, Fig. 65 2, perforated similarly to the front wall and having at its lower edge a hook 11 to catch inside the lower edge of the opening, its upper edge being held by buttons 12 on the shaft. On the inner back wall of the shaft 7c at intervals are shelves 13, one only of which is shown, that slope toward the front wall and for a purpose to be stated.

At the upper end of the front is an opening 14, guarded by rods to form a screen to 75 prevent large pieces of rubbish that might choke the sewer from entering. The top of the shaft 2 is closed by a cover, in the center of which is fastened a pipe 15, that extends upward to the sidewalk and is closed by a 80 cover 16.

The operation of the basin is as follows: In a rainfall the water flowing into it from the street will escape through the openings 8, leaving all particles of rubbish in the basin 85 that will not pass the openings 8. If the rainfall is excessive, so that these openings will not take it off at once, the surplus will pass through the openings 14, the larger particles of rubbish and ordinarily the lighter being 90 caught by the screen 14. As soon as the rainfall ceases or decreases sufficiently to permit the openings 8 to take the water it will fall, leaving only the sand and heavier particles at the bottom of the basin. As the water 95 passes through the openings 14 it strikes, in falling, the shelves 13 and is thus deflected against and washes the inner face of the perforated wall. After the rainfall or in dry seasons this wall can at any time be washed to 100 keep it clean by running water through the pipe 15 from hose or other means, the water being in the same manner deflected by the shelves 13. The shaft 2 is preferably made

of iron, but may be of earthenware or other material, the desirable features being that it be non-absorbent and non-corrosive and of sufficient rigidity to subserve its purpose.

5. What I claim is—

1. The combination with a catch-basin of a shaft having a side consisting of a flat plate of non-absorbent material adapted to form a part of the wall of the basin, the lower portion of said side being provided with fine openings narrowed toward the interior of said basin and the upper portion with a large opening guarded with bars, the lower end being curved to connect with a sewer, substantially as shown and described.
15. 2. The combination with a catch-basin of a shaft having a perforated side adapted to form a part of the basin-wall, the lower end being curved outward and upward to form a connection with a sewer, and an adjustable plate in said curved portion to form a trap to prevent the escape of gas, substantially as shown and described.
20. 3. The combination with a catch-basin of a shaft having a perforated side adapted to form a part of the wall of the basin, and its lower end adapted to be connected with a sewer, of

shelves located in said shaft opposite and sloping toward the perforated side, substantially as shown and described.

4. The combination with a catch-basin and a shaft having a perforated side adapted to open into the basin, and with its lower end adapted to be connected with a sewer, and sloping shelves located in said shaft opposite 35 said perforated side, of a pipe in the top of said shaft for turning water on said shelves, substantially as shown and described.

5. The combination with a catch-basin of a shaft having a perforated side adapted to form 40 a part of the basin-wall, the lower end being curved outward and upward to form a connection with the sewer, and an adjustable plate in said curved portion to form a trap 45 for sewer-gas, of an opening in said perforated wall adjacent to said plate, and a detachable door to close said opening, substantially as shown and for the purpose specified.

In testimony that I claim the above I hereunto set my hand.

JAMES J. MAHONY.

In presence of—

C. P. HUMPHREY,
C. E. HUMPHREY.
